UNITED STATES PATENT OFFICE.

GEORGE ELBREG, OF COLUMBUS, OHIO.

TILE-MACHINE.

SPECIFICATION forming part of Letters Patent No. 267,847, dated November 21, 1882.

Application filed May 2, 1882. (No model.)

To all whom it may concern:

Be it known that I, GEORGE ELBREG, a citizen of the United States, and a resident of Columbus, in the county of Franklin and State 5 of Ohio, have invented certain new and useful Improvements in Tile-Machines, of which the following is a specification.

My invention relates to a tile-machine.

The object of my invention is to press the tile on carrier-plates, which are first oiled; then the clay or tile blank is placed upon carrier-plates, passed under an oil-roller, thence carried between dies and into a die-box, where it is subjected to pressure to shape and form the tile, then delivered out of the dies by the automatic and intermittent action of the machine driven by power, the motion of the machine being imparted by means of an oscillating shaft, from which shaft all parts of the 10 machine primarily take their motion to successively carry out the various steps of the operation.

The various features and the mode of operation will be fully explained in the description 25 of the accompanying drawings.

Figure 1 is a side elevation of my machine for oiling the carrier-plates; Fig. 2, an end elevation of the same. Fig. 3 represents the carrier-plate. Fig. 4 is a perspective view of 30 the pressing-machine; Fig. 5, an end elevation of the same; Fig. 6, a plan view of the reversing-gear; Fig. 7, a longitudinal section on line xx , Fig. 5; Fig. 8, a detail view of one of the outside eccentrics operating the die-arms; Fig. 9, a detail view of die-arm with 35 die removed.

A A' A² represent the frame of my apparatus; a', an endless carrier traveling over pulleys a a'; a², carrier-blocks secured to belt 40 a'; B b, a ratchet and pawl; B', a belt connecting pulley b' to driving-pulley B², rigidly secured to shaft S.

C is a roller covered with sheep's pelt or other porous substance designed to hold oil; 45 c, the traveling plates, on which is placed the clay; c' are depending legs or hooks engaging with the carrier-blocks a²; c², angle-irons, which act as ways for plates c. The plates c are placed upon the angle-irons or ways c', 50 then, by means of the carrier-blocks a², are carried under roller C, which oils the surface. When they reach the other end of the machine

they are taken off by the operator and blanks of clay placed upon them, when they are ready for the second step.

D represents the frame-work of the pressing-machine; E E', driving-belt pulley-wheels, running in opposite directions, and mounted upon sleeves h, loosely rotating on shaft e.

E² represents a pinion mounted upon a 60 sleeve tight upon shaft e.

E³ represents a quadrant-gear having teeth meshing with those of pinion E², and mounted upon and keyed to shaft S.

F represents a shifting-lever, and f a shifting-frame for moving the sleeves h laterally upon shaft e; G G', clutch-teeth on the ends of the sleeves h h, which engage with similar teeth upon either end of clutch h'.

q q' represent clutch-gears upon the inner 70 hubs of the pulleys E E' and the outer ends of the clutches h, so as to allow the lateral movement of either of clutches h to engage with clutch h' for communicating motion from either of the pulleys E E' to pinion E².

H represents a roller covered with porous substance, similar to roller C, for oiling the top of the clay out of which the tile is to be formed.

L L' indicate a compound link-lever, operated by shaft S by means of the crank-arm l' in the manner hereinafter described.

L² l l' m' indicate reciprocating adjusting mechanism connected to the adjusting-plate m, which travels on angle-iron ways M'. Lever L² is pivoted to the frame of the machine at s and connected by a slotted link, l', to the crank-arm l, secured to the shaft S.

M'' indicates angle-iron ways on the opposite end of the machine, on which plate c travels after being acted upon by the dies.

M indicates angle-iron ways, which are elevated in a plane above the ways M', so as to allow the adjusting-plate m to pass under the carrier-plate.

n n are adjusting or centering triggers.

O is the casing or die box to hold die-plates in pressing; O', the top face of the plunger-piston; o, the clay or tile blank; P, the upper die-plate; P', vertically-sliding arms secured to plate P.

P² represents guides, which are grooved to receive arms P'.

I I' I'' i represent a crank-lever and eccen-

tric mechanism; J, a slot in the frame of the machine.

When the operator removes the plates from the machine shown in Figs. 1 and 2 and fills them with blanks of clay, he places one upon ways M and pushes it forward under the roller H to oil the top of the blank to prevent its sticking to the die. Meanwhile the quadrant E² oscillates to the right, carries arm l in the direction shown by the arrow, thus drawing link l' in the same direction and throwing arm L², pivoted at s, to the right. This carries the adjusting-plate m with it back under the ways M upon ways M', as shown by dotted lines, Fig. 7, so that when the plate c, with clay o, passes out from under roller H and drops down upon ways M' the adjusting-plate m will be in the rear of it. When the shaft S rotates in the opposite direction the motion is reversed and the plate, with the tile-blank, is shoved along ways M' between the dies. When the shaft S rotates to the right the arm l', operating link L', draws arm L downward. At the same time the arm I, traveling to the left, operates arm I', thus rotating eccentric I² and allowing the press-beam K to drop down in slot J. Both ends of the arm L move down without changing the inclination and in unison with press-beam K, so that when press-beam K reaches the bottom of the slot J the inclination of arm L is unchanged. The plunger Q, resting upon roller r, journaled in beam K, drops with said beam. As soon as the plunger Q begins its downward motion the arms N engage with triggers n and operate them so as to close upon the plate c and center it upon the plunger, when it is ready for the pressure. When the plunger and beam K drop they carry the top die, P, and arms P' down, and this motion, by means of arm T, pivoted to the frame of the machine and to the eccentric t, rotates the eccentric, as shown by arrow, and throws arm P' down, so as to draw the top die, P, down upon the clay. These motions are all simultaneous with the downward motion of the plunger Q. After the beam K reaches the bottom of slot J, by the continued downward motion of the link L' and arm L the roller r' is brought to act upon the inclined bottom of plunger Q, and, traveling to the right, raises plunger Q, so as to lift plunger Q up and press the clay between the dies O² and P and form on the surface any desired ornamental figures or ribs conforming to the face of the dies. When the quadrant F³ has revolved far enough to the right to cause these motions to be performed they are stopped by means of a lug, g', upon its periphery engaging with the bracket f', as shown in Fig. 6, throwing the frame f over, so as to cause clutch-sleeves h to slide upon shaft e and throw loose sleeves of wheel E' out of engagement and at the same time that of wheel E into engagement with the other end of the sleeve h', thus reversing the motion of the quadrant, and with it the motions of the various levers

and arms before described. Lever F is moved to the right or left, so that sleeves h may be thrown out of or in gear at any period of the operation of the machine, and the motions instantly reversed at the will of the operator. In order to allow the operator to stop the machine at any point of its operation, the sleeves h are set far enough apart to allow the clutch-sleeve h' to rotate freely between them. Lever F and frame f are attached to clutch-sleeves h, so that both may be disengaged from the clutch-sleeve h' by a partial throw of lever F, as shown in Fig. 6, or the motion may be at any time reversed by a full throw of the lever. The die is emptied and the machine set for a second operation by reversing the motion by lugs e' g'. The beam K, being raised by means of the eccentric I², carries the arms P', together with the eccentric t, upward, and because the link or arm T is pivoted to the frame of the machine, arm T draws the eccentric over to the right until it resumes the position shown in the drawings, Fig. 8, thus raising arms P', so as to lift the upper die, P, clear of the clay and above the plane of its travel, which allows the pressed tile, together with the plate c upon which it rests, to be pushed forward on ways M² by the next succeeding plate, as shown in Fig. 4. These motions are repeated automatically and successively, rendering the management of the machine very simple and easy. When the tiles pass out of the die upon the ways M² they are taken by the operator and emptied and the plates c placed upon the ways of the machine, (shown in Fig. 1,) when the same operations are repeated.

The machines shown in Figs. 1 and 4 are placed side by side, the pulley B² being mounted upon and driven by the same shaft, S, as quadrant E². The legs or hooks c' on the bottom of plate c serve as handles for the operator to remove them from and replace them upon the machine. The pulley b' is attached to the shaft of pulley a by any usual clutch device, which allows it to run backward as an idler when shaft S moves to the right. When the motion of shaft S is reversed ratchet and pawl B b checks the backward movement of the carrier belt or apron.

I claim—

1. The oiling-machine composed essentially of traveling belt a, carriers a², ways c², and oiler-roller C for oiling faces of carrier-plates c, substantially as herein set forth.

2. A tile-pressing machine composed essentially of the right and left driving-pulleys E E', quadrant E³, and gear E², with reversing and clutch devices for operating the dies by the automatic reversal of quadrant E³, substantially as herein set forth.

3. In a tile-pressing machine, the automatically-reversing quadrant-shaft S, in combination with the crank l, and links l' L², pivoted to and operating reciprocating carrier m, substantially as herein set forth.

4. In combination with the oscillating shaft S, cranks I I^2 for automatically operating the link-lever mechanism pivoted to said cranks for raising, lowering, and compressing the dies, substantially as herein set forth. 5
5. In combination with the oscillating shaft S, the crank I^2 , link-levers L L', and eccentrically-pivoted rocking press-beam K, and inclined plunger Q, for compressing the tile in the die-box, substantially as herein set forth. 10
6. In combination with the rising-and-falling plunger Q, the arms N, attached thereto, and the pivoted triggers n for centrally adjusting the carrier-plate c, substantially as herein set forth. 15
7. In combination with the oscillating shaft S and crank-arms I I^2 , and the link-lever pressing mechanism, plunger-dies O² P and die-box O, adapted to act intermittently and automatically, substantially as herein set forth. 20
8. The combination of the rising-and-falling plunger Q, with its die O², the die-arms P', die P, and die-box O, combined with and operated by means of levers L I, and eccentric I², and press-beam K, substantially as herein set forth. 25
9. In combination with the oscillating shaft S, right and left driving-pulleys E E', and the reversing clutch mechanism h h', substantially as herein set forth. 30
10. In combination with the oscillating shaft S, right and left driving-pulleys E E', the reversing clutch mechanism h h', frame f, and lever F, substantially as herein set forth. 35
11. In combination with a tile-machine having ways M' M², the elevated ways M and oiler-roll H, substantially as herein set forth. 40
12. The carrier-plate c, provided with hooks or arms c', adapted to hold the tile and move in ways, substantially as herein set forth. 45
13. In a tile-machine, the presser-die O², provided with groove v, adapted to receive and hold carrier c while the tile is being pressed between the dies in the presser-box, substantially as herein set forth. 50
14. In combination with the die-pressing machine operated by the oscillating shaft S, the oiling-machine containing the endless belt-ways, and oiler-roller C, the operative parts of which are intermittently actuated by the said oscillating shaft, substantially as herein set forth. 55

In testimony whereof I have hereunto set my hand in the presence of two subscribing witnesses.
